Mich., assignors to United-Carr Fastener Cor-
poration, Cambridge, Mass., a corporation of
Massachusetts

Application April 16, 1941, Serial No. 388,894

6 Claims. (Cl. 201—63)

The present invention relates to resistance socket installations of the type designed for the operation of an electric lamp or other signal or device by reduced voltage and aims generally to improve existing installations of this kind.

In the accompanying drawing we have illustrated a preferred form of our improved installation in which:

Fig. 1 is a side elevation of the installation embodying the invention;

Fig. 2 is an end view thereof;

Fig. 3 is a longitudinal sectional view taken on the line 3—3 of Fig. 2;

Fig. 4 is a perspective view of the grounding lug; and

Fig. 5 is a sectional view of a modified form of socket.

According to the invention, an electric lamp 10 or other electrical signal or device may be mounted in a sheet metal socket 11, embodying our invention, the entire assembly being simple and compact and safe in handling.

Advantageously the socket 11 is of the snap-on type adapted to be snapped upon an apertured support. One form of socket of this type is illustrated and comprises a sheet metal socket member having an outwardly flared end 12. An attaching ring 13 formed with a plurality of bowed resilient fingers 14 is secured to the flared end 12 by means of a cap ring 15 so that the fingers surround the open socket end and extend outwardly beyond the cap ring 15. A lamp bulb 10 may be inserted in the open socket end and secured therein by reason of the bayonet slot 16, and the assembled socket and lamp may be attached to a support 17 by a direct push, the fingers 14 having a snap fastener engagement with the edge of the support 17 surrounding an aperture 18 therein through which the lamp 10 is passed.

Current may be supplied to the lamp from any suitable source, such as a battery 19, in the case of motor vehicle signals, one lead 20 being connected to a lamp base contact (not shown) within the socket, as is usual and the other terminal 21 grounded to the socket shell.

In certain installations it is desired to supply a relative low or reduced voltage to the lamp or signal when the voltage supply is higher than desired and it is our aim to combine with the socket a suitable resistance to provide for the reduced voltage. According to the present invention, this is accomplished by embodying a resistance to the grounded sides of the circuit.

In the illustrated embodiment a grounding

lug or member 22 is provided which is preferably L-shaped, one leg of which is formed with an aperture 23 adapted to fit over a tubular rivet or extension 24 on the end of the socket 11 opposite the lamp-receiving end. The apex of the lug 22 is preferably bent as at 25 to conform to the contour of an annular bead 26 on the socket 11. The other leg 27 of the grounding lug is preferably straight for a substantial length, for contact with the shell of the socket 11, and terminates in an eye 28.

Resistance is provided by a coil 29 composed of a plurality of windings of an insulated conductor 30 wrapped tightly around the socket 11 shell and leg 27 of the grounding lug and electrically connected at one end to the eye 28. The other end of the conductor 30 is connected to a suitable connector 31 mounted on an insulated arm 32 fitted over the rivet 24 and fastened thereby to the end of the socket. As the tubular rivet is flattened over the outer face of the insulated arm 32, the arm and apertured end of the lug 22 will be firmly secured in assembled relation with the lug 22 in electrical contact with the shell of the socket at the end and throughout a substantial length of the side thereof.

Preferably the conductor 30 is a glass insulated wire although other types of insulation may be used.

30 The improved resistance socket provides a simple, compact and efficient construction that may be associated with the snap-on type of socket member, and the entire lamp and socket assembly readily inserted in and removed from an apertured support by a direct axial thrust.

35 Although the invention is particularly adapted for providing a resistance for snap-on types of socket as above described, it is not restricted to such use. Alternately, the socket may be mounted on an insulated support 33 (see Fig. 5), being connected thereto by a tubular rivet 24 in the manner above described. The member 33 thus serves as a support for the socket as well as an insulated arm for the spaced connector 34. In 40 this type of installation, obviously the snap fastener fingers are not necessary and the lamp-receiving end of the socket may be plain.

45 Our invention is not to be interpreted narrowly as limited to the specific construction shown and described, which is intended merely as illustrative, but includes as well equivalent constructions as fall within the scope of the appended claims.

We claim:
50 1. A resistance socket installation comprising

a sheet metal socket formed at one end for the reception of an electrical device, an electrical circuit for said socket including a base contact within said socket for said device and a resistance coil wrapped around the body of the socket, one end of the coil being electrically connected to said socket and the other end being insulated therefrom and connected to a source of electrical energy.

2. An electric socket installation comprising a sheet metal socket formed at one end for the reception of an electrical device, an electric circuit for said device including an L-shaped grounding lug secured to said socket with one leg thereof disposed longitudinally of said socket and in contact therewith, a resistance coil wrapped around said socket and lug, one end of said conductor being electrically connected to said lug and the other end being electrically connected to a source of electrical energy.

3. A resistance socket installation comprising an apertured support, a socket member formed of tubular sheet metal having a lamp-receiving opening at one end, means adjacent the lamp-receiving end of said socket member for snap-fastening engagement with the aperture of said support, an electrical circuit for said socket including a base contact within said socket, and a resistance coil wrapped directly around the body of said socket, one end of the coil being grounded to said socket and the other end connected to a terminal insulated therefrom.

4. A resistance socket installation comprising an apertured support, a socket member formed of tubular sheet metal having a lamp-receiving opening at one end, means adjacent the lamp-receiving end of said socket member for snap-fastening engagement with the aperture of said support, an electrical circuit for said socket in-

cluding a base contact within said socket, and a resistance coil wrapped directly around the body of said socket, a grounding lug fastened to said socket and formed with a part extending longitudinally thereof in contact therewith and positioned between the socket and the coil, one end of the coil being connected to the grounding lug and the other end connected to a terminal insulated therefrom.

5. A resistance socket installation comprising a socket member formed of tubular sheet metal having a lamp-receiving opening at one end and a tubular rivet of reduced diameter at the other end, an electrical circuit for said socket including a contact within said socket and a resistance coil wrapped directly around the body of the socket and grounded at one end thereto, an insulating body secured to said socket by said tubular rivet, and a terminal on said insulating body spaced from said socket for connection with the end of the resistance coil opposite the end grounded to the socket.

6. A resistance socket installation comprising a socket member formed of tubular sheet metal having a lamp-receiving opening at one end and a tubular rivet of reduced diameter at the other end, an electrical circuit for said socket including a contact within said socket and a resistance coil wrapped directly around the body of the socket, an L-shaped metal grounding member having one end positioned on said rivet and formed with a part extending longitudinally of the socket and making a line contact therewith, and a terminal on said insulating body spaced from said socket for connection with the end of the resistance coil opposite the end grounded to the socket.
